TUBULAR CORE

Harry S. Price, Dayton, Ohio

Application December 29, 1941, Serial No. 424,748

3 Claims. (Cl. 25—128)

This invention relates to tubular cores for use in casting concrete or cementitious material to provide passages in the cast product.

One object of the invention is the provision of a radially expandable fluid tight tube for coring substantially circular passages in the casting of concrete or the like, the tube normally having a corrugated shape when deflated and assuming a substantially circular shape when inflated.

Another object of the invention is the provision of a tube for coring passages in concrete, the tube being so constructed as to expand radially when inflated and to disconnect or strip itself from the partly set concrete as the tube is deflated so that an effective stripping action is initiated throughout the length of the cored passage at a number of stripping zones having a predetermined radial spacing.

Another object of the invention is the provision of a radially expandable fluid tight tubular core for making circular passages in casting concrete, the tube having a vulcanized rubber wall of substantially corrugated form and provided with fabric or cords which limit the diameter of the tube when inflated and which maintain the tube at substantially uniform length under varying internal pressure conditions.

Other objects and advantages of the invention will be apparent from the following specification, the appended claims and the accompanying drawing.

In the drawing.

Fig. 1 is a transverse section of a tubular core embodying the present invention;

Fig. 2 is a side elevation of a portion of the core, with a fragment of outer rubber removed to disclose the fabric reinforcement; and

Fig. 3 is a perspective view showing the use of the tube in casting a concrete beam.

The drawing shows a preferred embodiment of the invention as a radially expandable pressure tight tubular core for use in making precast concrete beams having one or more longitudinally extending circular passages. Referring more particularly to the drawing, in which the same reference numerals have been used to designate like parts in the several views, 10 generally designates an elongated tube, of any desired length, and adapted to be subjected to internal pressure after being applied to the form 11 in which the concrete or other cementitious material is to be cast. In making precast concrete beams an elongated trough-like form, as shown in Fig. 3, may be employed, the end walls 12 of the form having openings 13 which correspond in diameter

to the diameter of the longitudinal passages to be cored in the form. These passages may be about 4 or 5 inches or more in diameter. As shown in Fig. 3 one of the core tubes 10 is in place, projecting through the end walls 12 and inflated to the diameter of the openings, it being understood that a second core tube is to be positioned in the adjacent openings in the end walls before the concrete is poured into the form.

10 The tube 10 has a vulcanized rubber wall of substantial thickness. The thickness of the wall of a five inch diameter tube may be about three-eighths of an inch and its hardness may be comparable to that used in automobile tire construction. Fixed to and preferably embedded between the inner and outer surfaces of the rubber wall is a fabric reinforcement 15 including fabric cords which extend continuously around the axis of the tube and transversely of that axis. These annularly extending cords are preferably interwoven with other longitudinally extending cords reaching throughout the length of the tube. If desired, a series of spaced reinforcing wires or rods 17 may be embedded in the rubber walls. At their 15 ends the tubes are closed by end portions 18 and 19, at least one of which is provided with a valve 20 through which air or liquid under pressure may be supplied to inflate the tube, and operable to permit the release of the pressure fluid.

20 In its normal or deflated condition, the wall of the tube assumes a substantially corrugated cross sectional form as indicated in Fig. 1, being vulcanized to that form in the process of its manufacture. The fabric reinforcement 15 lies substantially parallel to the outer surface of the tube, following the corrugations of the tube walls. When the tube is subjected to pressure, it expands radially, the inwardly extending convolutions being pressed outwardly, and as the pressure 25 increases, the inwardly extending convolutions finally reach an expanded condition as indicated in dotted lines in Fig. 1, in which the outer surface of the tube is substantially cylindrical and considerably larger in diameter than a circle touching the convolutions of the deflated tube, since the curvature of the inwardly extending convolutions of the deflated tube is considerably greater than the curvature of the expanded tube. The maximum diameter of the inflated tube is limited, however, by the total annular length of the 30 fabric reinforcement, since the fabric cords, which are not capable of stretching any substantial distance, extend perpendicular to the direction of the tube axis. When the tube is inflated, therefore, in spite of any differences in rigidity or

minor differences in wall thickness throughout the length of the tube, the entire tube will have a substantially uniform diameter, those unsupported portions of the tube lying between the supporting end walls 12 having substantially the same diameter as the openings 13 in which the end portions of the tube are located. The openings 13 are made to correspond to the inflated tube diameter so that the tubes will be held with sufficient tightness to prevent any substantial loss of concrete through those openings.

The length of the tube remains substantially constant as the tube is inflated, since the longitudinally extending cords lying parallel to the tube axis prevent tube elongation, and the wires or rods 17, if those are employed, also reinforce the tube against longitudinal expansion. After the concrete is partially set so that the cast concrete beam will retain its shape, the tubes 10 are deflated by opening the valves 20. The walls of the tube then return to their corrugated form, due to the tension created in the rubber, and the separation or stripping of the rubber from the concrete initially takes place along radially spaced longitudinally extending zones where the tension of the rubber is greatest, namely at those points which will ultimately be returned to form the inner convolutions of the deflated tube. As the pressure inside the tube is relieved, the separation of the rubber from the concrete continues from these initial separation lines, the rubber stripping from the concrete in annular directions towards opposite sides of the initial separation zones. By the time the deflation of the tube is complete, the entire tube is free from holding engagement with the concrete, and it may be readily withdrawn endwise from the concrete casting and from the form in which the beam was cast. It is preferred, in making beams in the manner described, that the tube should be deflated after the concrete is set sufficiently to maintain its shape but before the concrete becomes so hard as to make an adhering connection with the tube or core, but even though the tube is not deflated at the most opportune time in the setting of the concrete, it will separate itself when it is deflated, since a very large proportion of the contractive force of the tube is initially applied to the expanded rubber walls at localized longitudinally extending zones to start the stripping action, which then continues until the tube is completely separated from the concrete.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A radially expandable fluid tight tube for coring substantially circular passages in concrete, said tube having a vulcanized rubber wall

of substantial thickness inherently assuming a corrugated cross sectional form when deflated and inflatable to assume a cross sectional form which is substantially circular and of greater outside diameter than a circle touching the outside of the convolutions of the deflated tube, said wall having flexible reinforcing means imbedded therein and extending substantially transversely of the longitudinal axis of the tube normally in 10 a corrugated path and limiting the diameter of the tube by assuming a substantially circular path when the tube is inflated, said reinforcing means upon deflation of said tube causing initial separation of said tube to begin in and progress 15 from spaced areas located circumferentially thereof.

2. A radially expandable fluid tight tube for coring substantially circular passages in concrete, said tube having a vulcanized rubber wall 20 of substantial thickness inherently assuming a corrugated cross sectional form when deflated and inflatable to assume a cross sectional form which is substantially circular and of greater outside diameter than a circle touching the outside of the convolutions of the deflated tube, said wall having fabric reinforcement embedded therein and tending to maintain said corrugations in the absence of fluid pressure, said reinforcement including cords extending generally 25 annularly transversely of the longitudinal axis of the tube but in a normal corrugated path to limit the outside expanded tube diameter and additional cords extending axially of the tube and maintaining the tube length substantially 30 constant under different internal pressure conditions, said reinforcement upon release of internal pressure developing a restoring force to return said core to corrugated form.

3. A radially expandable fluid tight tube for 35 coring substantially circular passages in concrete, said tube having a vulcanized rubber wall of substantial thickness inherently assuming a corrugated cross sectional form when deflated and inflatable to assume a cross sectional form 40 which is substantially circular and of greater outside diameter than a circle touching the outside of the convolutions of the deflated tube, said wall having flexible reinforcing means formed integrally therewith and extending substantially 45 transversely of the longitudinal axis of the tube normally in a corrugated path and limiting the diameter of the tube by assuming a substantially circular path when the tube is inflated, said reinforcing means being under tension when the tube is inflated and developing a force when said 50 tube is deflated for causing separation of the tube from the formed passage initially in a series of points spaced circumferentially around its periphery and corresponding to the low points of the corrugations, and closure means at the ends 55 of the tube, said closure means including a valve for supplying pressure fluid to the tube.
